TAILPIECE VIBRATO FOR STRING
INSTRUMENT

Paul A. Bigsby, Downey, Calif.

Application November 15, 1952, Serial No. 22,312

Term of patent 14 years

(Cl. D56—3)

To all whom it may concern:

Be it known that I, Paul A. Bigsby, a citizen of the United States, residing at Downey, in the county of Los Angeles and State of California, have invented a new, original, and ornamental Design for a Tailpiece Vibrato for String Instrument, of which the following is a specification, reference being had to the accompanying drawing, forming part thereof, in which:

Fig. 1 is a perspective view of a tailpiece vibrato showing my new design in association with a string instrument, the latter being illustrated in phantom;

Fig. 2 is a top plan view of the tailpiece vibrato, slightly enlarged;

Fig. 3 is a side elevational view thereof;

Fig. 4 is a front elevational view thereof;

Fig. 5 is a rear elevational view thereof; and

Fig. 6 is a bottom plan view thereof.

The dotted line showing in the drawing is for illustrative purposes only.

I claim:

The ornamental design for a tailpiece vibrato for string instrument, substantially as shown and described.

PAUL A. BIGSBY.
